UNITED STATES PATENT OFFICE.

GEORGE HENRY CHALLENGER, OF WESTMINSTER, LONDON, ENGLAND, ASSIGNOR TO
VICKERS LIMITED, OF WESTMINSTER, ENGLAND.

MOUNTING FOR GUNS CARRIED BY AEROPLANES AND SIMILAR AIRCRAFT.

1,298,885.

Specification of Letters Patent.

Patented Apr. 1, 1919.

Application filed July 6, 1917. Serial No. 179,073.

To all whom it may concern:

Be it known that I, GEORGE HENRY CHALLENGER, a subject of the King of Great Britain, residing at Vickers House, Broadway, Westminster, in the county of London, England, have invented certain new and useful Improvements in or Relating to Mountings for Guns Carried by Aeroplanes and Similar Aircraft, of which the following is a specification.

This invention relates to mountings for guns carried by aeroplanes and similar aircraft.

When the aeroplane carrying the gun is in motion and the gun is being elevated while pointing ahead, the pressure of the air on the gun will have an appreciable effect on the ease with which the gun can be elevated and depressed. Thus if the gun be elevated, starting from a horizontal position, the pressure of the air will exert on the gun a gradually increasing turning moment tending to further elevate the gun. During the first portion of the elevation this turning moment is opposed by the turning moment due to the weight of the gun tending to depress it about its horizontal pivot. The latter turning moment is greater than the first mentioned turning moment until a certain angle of elevation is reached at which point the two moments are balanced. If, however, the gun is elevated past this point the turning moment due to the pressure of the air will be greater than the other turning moment. This condition of affairs militates against effective operation of the gun and to overcome the difficulties arising therefrom we, according to the present invention, provide a spring device which is of such a character that it will give a graduated assistance to the elevating movement of the gun until the aforesaid point in elevation is reached, at which time the spring device will no longer exert a turning moment upon the gun; when, however, the gun is elevated beyond this point the spring device will exert a graduated opposition to the elevating movement. In other words the spring device exerts upon the gun in elevation and depression a turning moment opposite and equal or approximately equal to the resultant of the turning moments due to the weight of the gun and the pressure of

the air and the gun is thus approximately balanced at all angles of elevation when 55 pointing ahead or approximately ahead.

When the gun is being trained from its ahead position the pressure of the air on the gun will exert a training turning moment and this turning moment will reach its maximum when the gun is in a position at right angles to the line of flight of the aeroplane and is horizontal. In order to balance this turning moment and thus facilitate the training of the gun we provide a spring device which is so constructed as to balance or approximately balance this turning moment in training when the gun is more or less horizontal; the turning moment exerted by this spring device gradually increases 60 during the training of the gun in either direction from its ahead position and reaches the maximum when the gun is pointing at right angles to the line of flight of the aeroplane.

In order that the said invention may be clearly understood and readily carried into effect the same will now be described more fully with reference to the accompanying drawings, in which:—

Figures 1 and 2 are respectively a side elevation and a plan of an aeroplane gun mounting showing diagrammatically an advantageous form of the aforesaid spring balancing devices, and

Fig. 3 is a view showing a modified form of the spring balancing device.

A is a fuselage of the aeroplane and 'A' is the gun. The gun is carried by arms 'a', 'a' which are pivoted at 'a', 'a' to a ring 'a' 90 rotatably mounted at the upper end of a wall or chamber A in the manner described in the specification of our earlier application for British Patent No. 9389 of 1915. The ring and the arms are shown in different 95 positions in the two figures of the drawing.

One of the arms 'a', 'a' is shown in Figs. 1 and 2 provided with an extension 'a' connected to a cord or chain A which passes between two pulleys 'a', 'a' carried by a 100 bracket A attached to the ring 'a', the said cord or chain being connected to a helical tension spring A attached to the said ring. In the position of the gun as shown in Fig. 1 the turning moment about the pivots 'a', 'a' 105 due to the weight of the gun is supposed to

preponderate over the turning moment due to the air pressure and the spring A^s is exerting upon the arms a turning moment to balance the gun, the cord or chain A^s at this 5 time bearing against the pulley a^4 . As the gun is farther elevated this balancing turning moment becomes smaller until when the point of attachment of the cord or chain A^s to the extension a^s lies in a plane passing be- 10 tween the pulleys a^4 , a^{4s} and containing the axis of the pivots a' , a' , the spring will no longer exert any turning moment upon the arms. This represents the position at which the two turning moments due to the air pres- 15 sure and the weight of the gun are balanced. If the gun be elevated beyond this point the cord or chain A^s will pass into contact with the other pulley a^4 and the spring A^s will in consequence exert upon the arms a , a' , a balancing turning moment in opposition 20 to the turning moment due to the pre-ponderating air pressure, this balancing turning moment increasing with the angle of elevation of the gun.

25 To a bracket b^s on the ring a^s is attached one end of a cord or chain B which passes between two pulleys b , b' and over a third pulley b^2 all situated on the fuselage and this cord or chain is connected to a helical 30 tension spring B' attached to the fuselage. In Fig. 2 the gun is shown as having been trained to the right of the center line of the fuselage and the spring B' is at this time exerting upon the ring a^s , in opposition to the turning moment due to air pressure, a balancing turning moment which reaches the maximum when the gun has been trained to fire at right angles to the center line and becomes zero when the gun is firing directly 35 ahead at which time the point of attachment of the cord or chain B with the bracket b^s lies in a plane containing the axis of the ring a^s and passing between the pulleys b , b' .

40 The helical tension spring A^s may be replaced by a clock spring carried by the ring a^s , one end of this spring being fixed and the other end connected to a movable casing attached to the cord or chain A^s . 45 Similarly the spring B' may be replaced by a clock spring one end of which is connected to the fuselage, the other end to a movable casing attached to the cord or chain B . It is preferred however to employ the ar- 50 rangement shown in Fig. 3 in which C is the clock spring connected at one end at C^s to a rotatable casing C' and anchored at the other end to a part C^2 . In the example shown the spring is intended to take the 55 place of the spring A^s and the parts A^s , a^s , a^4 , a^{4s} of Figs. 1 and 2 and is arranged concentric with the pivots a' , a' . The casing C' is connected to one of the arms a , a' and is rotatably mounted upon a spigot on the 60 training ring a^s and the part C^2 is connected 65 to or forms part of the said training ring. One such spring device is preferably used for each arm. In this figure the arm a is assumed to be in the neutral position in which the turning moments due to the 70 weight of the gun and the pressure of the air are balanced as aforesaid and in this condition of affairs the spring C is deenergized and consequently does not exert any turning moment upon the arm a . If the 75 arm be elevated beyond this neutral position the point C^s will move in a clockwise direction and the spring will be energized to exert a balancing turning moment in opposition to the turning moment due to the 80 preponderating air pressure, while if the arm be depressed from the neutral position the point C^s will move in an anti-clockwise direction and the spring will be energized to exert a balancing turning moment in opposition to the turning moment due to the pre- 85 ponderating weight of the gun. A similar arrangement of spring device may also be used for balancing the training turning mo- 90 ment of the gun, the casing being angularly displaced in synchronism with the training movement of the gun. In this case the spring will be in its deenergized or neutral position when the gun is pointing ahead and the spring will be energized by displace- 95 ment of the movable end of the spring in reverse directions when the gun is trained to the right and to the left of its ahead position.

96 It is to be understood that instead of helical tension springs or clock springs we may use other springs. We may, for example use india rubber cords or strands.

100 What I claim and desire to secure by Letters Patent of the United States is:—

1. In a mounting for a gun carried by an aircraft, means for exerting upon the gun in elevation and depression a turning moment opposite and substantially equal to the resultant of the turning moments due to the 110 weight of the gun and the pressure of the air.
2. In a mounting for a gun carried by an aircraft, a spring device for exerting upon the gun in elevation and depression a turn- 115 ing moment opposite and substantially equal to the resultant of the turning moments due to the weight of the gun and the pressure of the air.
3. The combination with a gun carried by 120 an aircraft, of a ring rotatably mounted on the aircraft, arms pivoted to the ring and supporting the gun and a spring device for exerting upon the arms in elevation and de- 125 pression a turning moment opposite and substantially equal to the resultant of the turning moments due to the weight of the gun and the pressure of the air.
4. In a mounting for a gun carried by an aircraft, means for exerting upon the gun a 130

- training turning moment opposite and substantially equal to the training turning moment due to the pressure of the air.
5. In a mounting for a gun carried by an aircraft, a spring device for exerting upon the gun a training turning moment opposite, and substantially equal to the training turning moment due to the pressure of the air.
- 10 6. In a mounting for a gun carried by an aircraft, the combination with a ring which is rotatably mounted on the aircraft and which carries the gun, of a spring device for exerting upon the gun a training turning moment opposite and substantially equal

to the training turning moment due to the pressure of the air.

7. An aircraft gun mounting provided with training balancing means comprising a crank member, a spring connected to said crank member, and means for driving said member to move in synchronism with the training of the gun whereby the spring exerts upon the gun, through the crank, a turning moment opposite and equal or substantially equal to that exerted upon the gun by the air. 20 25

In testimony whereof I affix my signature.

GEORGE HENRY CHALLENGER.
